ABSTRACT OF THE DISCLOSURE

A centrifugal compressor capable of stable operation under low volumetric flow rates. An annular ring, rotatable about the axis of the compressor is operably connected to inlet guide vanes and a diffuser restriction ring to provide programmed restriction of the inlet and diffuser passages in relation to the compressor loading.

This invention relates to gas compression equipment. More particularly, this invention relates to centrifugal gas compressors. Still more particularly, this invention relates to centrifugal gas compressors subjected to large load variations.

One of the major problems arising in the use of centrifugal gas compressors for applications where the compression load varies over a wide range is flow stabilization through the compressor. The compressor inlet, impeller and diffuser passage must be sized to provide for the maximum volumetric flow rate desired. When there is a low volumetric flow rate through such a compressor, the flow becomes unstable. As the volumetric flow rate is decreased from a stable range, a range of slightly unstable flow is entered. In this range, there appears to be a partial reversal of flow in the diffuser passage creating noises and lowering the compressor efficiency. Below this range, the compressor enters what is known as surge, wherein there are periodic complete flow reversals in the diffuser passage, destroying the efficiency of the machine and endangering the integrity of the machine elements. Since a wide range of volumetric flow rates is desirable in many compressor applications, numerous modifications have been suggested to improve flow stability at low volumetric flow rates. One of the most accepted and successful modifications has been the addition of guide vanes in the inlet of the compressor to vary the flow direction and quantity of entering gas. However, since the instability at low flow rates is also related to the diffuser configuration, it would appear desirable to vary diffuser configuration in response to the load on the machine to provide a more flexible compressor.

It is therefore the chief object of this invention to provide a method of varying the capacity of a centrifugal compressor to provide a large range of stable flow rates.

It is another object of this invention to provide a centrifugal gas compressor having means therein to stabilize the gas flow therethrough at extremely low flow rates.

It is a further object of this invention to provide means for automatically interrelating inlet guide vane movement with movement of diffuser flow restriction means to optimize compressor efficiency over a wide range of flow rates.

The objects of this invention are attained by providing a centrifugal gas compressor with inlet guide vanes and diffuser restriction means. An annular control member, arranged for movement in a circular path, simultaneously effects the position of the inlet guide vanes and the diffuser restriction means to provide peak efficiency at any flow rate.

Other objects and features of my invention will be apparent upon a consideration of the ensuing specification and drawings in which:

2

FIGURE 1 is an elevational view, partly in section of a portion of a centrifugal compressor including the impeller, inlet guide vanes, and diffuser passage, the compressor incorporating my invention.

5 FIGURE 2 is a view taken along line II—II of FIGURE 1.

FIGURE 3 is a fragmentary elevational view, partly in section of the compressor in FIGURE 1, further illustrating the guide vane and diffuser restriction actuator means of my invention.

Referring more particularly to the drawing, there is shown a gas compressor 1 of the well-known centrifugal type wherein gas to be compressed is induced to flow in an axial direction into a vaned impeller connected to a suitable drive for imparting rotary motion thereto. As the gas is compressed during its travel through the compressor, it is directed radially from the impeller to a diffuser passage communicating with the tip of the impeller. The compressor includes a housing 2 with inlet passage 3 and diffuser passage 5. Only a portion of the housing is shown, it being understood that such a construction is conventional in equipment of the kind under consideration. An impeller 7, affixed to shaft 9 by nut 11 is provided in housing 2 between the inlet passage 3 and diffuser passage 5. Inlet guide vanes 13 journaled for rotation in housing 2 are positioned about the inlet passage to control the direction and quantity of gas flow therethrough. An annular control member 15 is mounted on balls 17 in stationary race 19 for movement in a circular path. A plurality of cam tracks 21 equally spaced circumferentially of annular control member 15 are provided for mating engagement with cam followers 23. Cam followers 23 are comprised of rollers 25 bolted on push rods 27. Push rods 27 are bolted to diffuser restriction ring 29 so that rotation of annular control member 15 will effect axial movement of diffuser restriction ring 29 within diffuser passage 5, note the position indicated in dotted lines, said movement conforming to the shape and size of the tracks 21.

Arms 31, on guide vanes 13 are connected to annular control member 15 by links 33 so that rotation of annular control member 15 will also effect rotation of guide vanes 13.

A control rod 35 is mounted for rotation about its longitudinal axis to rotate annular control member 15 by means of links 37 and 39 pivotally mounted therebetween. The control rod 35 can be rotated by any well-known means (not shown) such as electric, pneumatic or hydraulic positioners responsive to an operating condition of the compressor or its associated equipment which is indicative of the load on the compressor. Thus if the compressor were to be used in a refrigeration machine, the positioning means could be responsive to the temperature of the chilled water leaving the machine, this temperature being related to the quantity of refrigerant being lifted from the low side to the high side of the machine by the compressor. If the compressor were being used to compress air, the positioning means could be responsive to ambient temperature since this is an indication of the air density and therefore the quantity of air being compressed.

60 As can be seen in FIGURE 3, cam tracks 21 have a specialized configuration. The track is so designed that rotation of annular control member 15 will rotate the guide vanes from full open position to a 60% closed position without restricting diffuser passage 5. If a reduction in flow greater than that caused by the guide vanes in the 60% closed position is desired, further rotation of annular control member 15 will simultaneously move guide vanes 13 between 60% closed and 85% closed and move diffuser restriction ring to provide a diffuser capacity between 100% and 5% of maximum. If a greater reduction than this is desired, further rotation of annular control member 15 will hold the diffuser restriction ring

in the 5% diffuser capacity position and move guide vanes 13 between 85% and 100% closed. By correlating guide vane movement and diffuser restriction ring movement in the manner described above, the lift capacity of the compressor is maximized over the complete range of flow rates attainable.

While I have described a preferred embodiment of my invention, it is to be understood that my invention is not limited thereto, but may be otherwise embodied within the scope of the following claims.

I claim:

1. A centrifugal gas compressor comprising, a housing having an inlet passage and a diffuser passage formed therein, an impeller mounted in said housing between the inlet and diffuser thereof, a plurality of guide vanes pivotally mounted in the housing to vary the quantity of gas flowing through the inlet passage, diffuser restriction means including an annular diffuser member mounted for axial movement across the diffuser passage to restrict flow of gas therethrough, actuator means including an annular control member arranged for movement in a circular path about the inlet passage connected to said guide vanes and regulating means effective in response to and operable only after a predetermined movement of the annular control member and pivoting of said guide vanes for axially positioning said annular diffuser member in response to further movement of said annular control member.

2. A centrifugal gas compressor according to claim 1 wherein said regulating means includes a plurality of cam followers attached to said diffuser restriction means, said annular control member having a plurality of cam tracks

formed therein for engagement by said cam followers to move said diffuser restriction means in response to the circular movement of said annular control member.

3. A centrifugal compressor according to claim 1 wherein said actuator means further includes guide vane linkage between said annular control member and said guide vanes, said guide vane linkage means comprising arms, affixed to said guide vanes for rotation therewith, and, linking rods, pivotally connected to said annular control member and said arms to rotate said guide vanes when said annular control member is rotated.

4. A centrifugal compressor according to claim 1 wherein said actuator means further includes a control rod mounted in said housing for rotation therein, and, control rod linkage means, operably associated with said annular control member so that rotation of said control rod effects rotation of said annular control member.
